(57) **CLAIM**

The ornamental design for a hand-held scrubber, as shown and described.

DESCRIPTION

FIG. 1 is a perspective view of a hand-held scrubber showing our new design;

FIG. 2 is a left side view of the hand-held scrubber of FIG. 1;

FIG. 3 is a right side view of the hand-held scrubber of FIG. 1;

FIG. 4 is a front elevation view of the hand-held scrubber of FIG. 1;

FIG. 5 is a rear elevation view of the hand-held scrubber of FIG. 1;

FIG. 6 is an end view of the handle of the hand-held scrubber of FIG. 1;

FIG. 7 is a top plan view of the hand-held scrubber of FIG. 1; and,

FIG. 8 is a bottom view of the hand-held scrubber of FIG. 1.
